KILN.

1,199,016.

Specification of Letters Patent. Patented Sept. 19, 1916.

Application filed May 1, 1916. Serial No. 94,854.

To all whom it may concern:

Be it known that I, LACHLAN WALLACE McARTHUR, of the town of Montreal, West, Province of Quebec, Dominion of Canada, 5 manufacturer, have invented certain new and useful Improvements in Kilns; and I do hereby declare that the following is a full, clear, and exact description thereof.

My invention relates particularly to open- 10 top kilns and has for its object to provide a comparatively simple, easily and cheaply constructed open-top kiln adapted to operate with an up-draft.

More specifically stated, the invention 15 consists of a kiln having an open top, that is to say, with no roof whatsoever to the kiln chamber which has a series of chimneys along each side wall, the communication between the flue of each chimney and the kiln 20 chamber being effected by a plurality of horizontal flues converging to the chimney flue; while the floor is provided with a series of preferably regularly spaced tortuous flues effecting communication between the kiln 25 chamber and heat generators located beneath the floor.

For full comprehension, however, of my 30 invention, reference must be had from the accompanying drawings forming a part of this specification in which similar reference characters indicate the same parts, and wherein:

Figure 1 is a side elevation of a two chamber kiln partly in vertical sectional 35 view, the section being taken on line 1 1 Fig. 2, erected according to my invention; Fig. 2 is a part plan and part horizontal sectional view thereof, the section being taken on line 2 2 Fig. 3; Fig. 3 is a transverse vertical sectional view taken on line 3 3 Fig. 1; Fig. 4 is a fragmentary sectional view taken on line 4 4 Fig. 5; and Fig. 5 is a fragmentary side elevation of one of the side walls illustrating the arrangement of the flues 45 therein.

In erecting my improved kiln the ground upon which it is to stand is excavated in a series of parallel furnace chambers *b* disposed in aligned pairs, separated by the un- 50 excavated portion *c* forming a wall, the opposite ends of the excavation being open. These open ends are excavated to a greater depth to provide the furnace chamber proper *e*, this furnace chamber being lined 55 as usual with refractory material and the

surface of the higher level floor *f* is also covered with refractory material while the inner ends of the excavations presented by the division wall *c* are inclined upwardly toward each other. Side walls *k* and end walls *m* are erected in line with and above the open ends of these excavations thus forming an oblong chamber inclosed on four sides. The excavations are covered by grids consisting of two layers, the first layer being 60 slabs *p* resting at their ends on the opposite edges of the linings of the excavations and spaced slightly from the side walls and from one another, the upper layer consisting of similar slabs *r* provided with corner feet; 65 and these upper slabs being arranged over the spaces between the lower slabs thus with these lower slabs presenting a multiplicity of tortuous flues. The grids thus produced extend from the division wall *c* to the side 70 walls. Each furnace chamber may be provided with a grate suitable for burning coal, and pipes (not shown) for liquid fuel or gas. When coal is to be burned the pipes 75 are removed.

The chimney flues 3 extend downwardly through the chimneys to a short distance below the top of the side walls where they communicate with the interior of the kiln by horizontal flues 4 divided into series and 80 each series converging into one of the chimney flues. In order to accommodate flues of sufficient capacity each flue has a comparatively shallow mouth 5 in the interior face of the chamber and the flue turns at sub- 85 stantially right angles in the direction of its particular chimney flue and is decreased in width and increases in depth outwardly from the interior face of the wall to a portion 7 of the flue which leads to the chimney flue. These flue portions 7 are each 90 equal in measurement in a direction from the interior to the exterior of the wall, to one-third the corresponding measurement 95 of the chimney flue and of sufficient depth 100 to have each series of four wall flues substantially equal in capacity to the chimney flue. This arrangement of flues distributes the draft uniformly over the entire length 105 of the chamber.

I find that the efficiency of my improved kiln is increased by extending the length and dividing it by a division wall 10 into a pair of kilns as shown in Figs. 1 and 2.

The kiln is intended primarily for the 110

burning of brick and in order to dry out the moisture, or a portion of it, from the green brick they are usually placed in a drier which utilizes the waste heat from the 5 burning operation in the kiln. With this object in view the division wall 10 is made with a pair of internal flues 12 and 12 respectively communicating with the chambers through flues high up on the division 10 wall or slightly below the level of the flues 4. An underground flue 20 leads from beneath one end of the division wall and also beneath the flue 12, in the wall to the drying chamber not shown, and these division 15 wall flues communicate with the underground flue by flues 28 and 30 each controlled by a damper 31, the operating rod of which, 32, extends upwardly through the top of the wall. The usual car track 60 and 20 cars (not shown) are provided for charging and discharging the kiln.

Each furnace is provided with a door 70 and dampers 75 by which the fire or burning action therein can be regulated to suit 25 the requirements of the kiln.

Operation: In charging my improved kiln the bricks from the drier are laid on cars and run into the kiln chambers where they are stacked in a way to permit an up- 30 draft between them, the lower courses being stacked on the slabs of the grids only and not over the mouths of the tortuous flues. The preferred method of stacking my improved kiln and more particularly the two 35 lowermost courses, to present draft flues 100, is shown in Fig. 3. The bricks are built up to the top of the walls and consequently a short distance above the top or flues 4, the two top layers being set tight or platted.

40 When the heating is started either by building a fire on the grates or burning oil or gas in the furnace chambers, the hot gas arises from the furnace chambers through the tortuous flues in the grids and upwardly 45 through the interstices between the brick and is drawn toward the sides and ends of the kiln by the suction of the chimneys and through the wall flues 4; the effect being that the heat is distributed throughout the 50 entire chamber, and the burning and inflammable gases drawn by the independent flues 4 into the chimney flues 3 are diffused there- 55 through and flow thence under the influence of the draft in the chimneys to the open air which they reach in a practically perfectly burned condition. This distribution of the hot gases uniformly throughout the entire chamber is induced by the comparatively widely spaced inner ends of the outwardly converging flues 4.

Perfect control of the burning is obtained without disturbing the platting of the bricks within the chamber by the dampers in the furnace doors and chimneys; 60 the comparatively large number of heat

generators and chimneys permitting of such a distribution of heat through the kiln that the flow of burning gases is admitted throughout the entire area of the bottom of the burning chamber and the suction causes 70 a constant flow upwardly between the bricks. If it is found that the burning operation is not being carried on uniformly and that too little or too great heat is occurring at any particular point, this particular point, where- 75 ever it may be in the kiln, can be readily reached and regulated by the heat generator and chimney controlling the zone in which it is located.

When the burning operation in a kiln 80 is finished and the dampers 31 controlling the communication with that kiln are opened, the other dampers being closed, the fire is drawn or the oil or gas shut off, the furnace doors are kept closed and a suction 85 fan in the drying chamber is then started. The effect is that practically all the heat in the burning chamber is drawn off and utilized in the drier.

The advantage of this kiln is that when 90 in operation the heat is conserved to a maximum extent and the two or three top courses of bricks set tight, which is known to the trade as platting, the chimneys and flues through the medium of the combustion 95 chambers provide all the draft necessary to procure good and speedy burning with an open and up-draft kiln, and a degree of perfection is obtained which could not be realized heretofore without the enormously expensive down-draft type of closed kiln. And it is not necessary, as heretofore, with open-top kilns, for the burner to repeatedly go on 100 the top of the kiln to remove and replace bricks as required to control the draft and 105 burning operations.

Considerable advantage is derived from the grids, in that the lower course of bricks are not subject to the initial heat of the burning gases which are deflected by the tortuous paths in the grids, thus breaking up 110 the burning jets of gas and scattering the heat in all directions from each of the upper slabs. This prevents fusing of the lower courses.

I find that with this particular arrangement of drafts from the heat generators at the sides through the multiplicity of tortuous flues in the floor, through the flues in and near the tops of the walls to the chimneys, the heat has a desired tendency to flow 120 to the center of the kiln, thereby enabling the capacity of the chimneys and wall flues to govern this tendency and cause a uniform distribution of the heat throughout the entire kiln.

What I claim is as follows:

1. In a kiln for burning brick comprising side walls and end walls inclosing a kiln chamber with open top, a series of heat gen- 130

erators supplying gases at a high temperature to the bottom of the chamber, the combination with the chamber thus constructed, of means for causing an upward draft from 5 the generators through the chamber to the top thereof, said means consisting of chimneys forming integral upward extensions of the side walls and corners of the kiln chamber and having draft flues extending down- 10 wardly therefrom to a point a short distance below the level of the top of the walls, and flues in said walls divided into series, each series of flues being nested in the wall and converging into one of the chimneys. 15 2. In a kiln for burning brick comprising side walls and end walls inclosing a kiln chamber with open top, a series of heat generators supplying gases at a high temperature to the bottom of the chamber, the combination with the chamber thus constructed, of means for causing an upward draft from the generators through the chamber to the top thereof, said means consisting of chimneys forming integral upward ex- 20 tensions of the side walls and corners of the kiln chamber and having draft flues extending downwardly therefrom to a point a short distance below the level of the top of the walls, and flues in said walls divided 25

into series, each series of flues being nested 30 in the wall and converging into one of the chimneys, each of the said wall flues having a wide and relatively shallow mouth in the interior side of the wall decreasing in width and increasing in depth from the mouth to 35 a flue section parallel to the face of the wall and leading to the chimney flue.

3. An open-top up-draft kiln for burning brick consisting of a structure comprising side walls and end walls presenting a kiln 40 chamber, the side walls being provided with a plurality of chimney flues, a plurality of series of horizontal flues in the said side walls near their upper ends and divided into a plurality of series and each series converging 45 into one of the said chimney flues, the chimney flues and horizontal flues being constructed and arranged to produce an outward draft from the kiln chamber to the 50 chimneys.

In testimony whereof I have signed my name to this specification in the presence of two witnesses:

LACHLAN W. McARTHUR.
